BY
Neil D. Reston,
his ATTORNEY

UNITED STATES PATENT OFFICE.

HERBERT B. TAYLOR, OF ROCHESTER, NEW YORK, ASSIGNOR TO GENERAL RAILWAY SIGNAL COMPANY, OF ROCHESTER, NEW YORK.

SKATE MACHINE.

Application filed November 12, 1926. Serial No. 147,974.

This invention relates to an emergency stop device for stopping railway cars and trains, and has more particularly reference to means for holding such device and moving it from an inactive to an active position, and vice versa.

This application is a continuation in part, of applicant's copending application, Ser. No. 72,264 filed Nov. 30, 1925, for skate machines, and reference is made to such application for a detailed showing and description of parts only broadly described in this case.

In railway practice, it sometimes occurs, particularly in classification yard systems, that track brakes operate improperly, or the operator has failed to place such brakes in their active braking position, so that cars will collide at dangerous speeds and injure one another. To avoid this possibility it is usual practice to place a skate on the track ahead of such cars, onto which the cars can ride and be retarded by sliding their front wheels along the track.

In the employment of power operated means for placing such skates, or derails if desired, on the tracks, and removing them therefrom, it is necessary that the skate be securely enough held by such means to retain it from being separated from the holding means by mistake while it must be held so that it can be slid free from its holding means, when a car wheel rides up on it and tends to slide the skate along the track rail.

With the above and other objects in mind it is proposed, according to this invention, to provide a power operated skate placing means, which will securely hold the skate in fixed position, and will allow the skate to be readily detached from the placing means, by action of a car wheel riding upon it and tending to slide it along a track rail.

Further objects, purposes, and characteristic features of the invention will appear as the description progresses, reference being had to the accompanying drawing, showing, solely by way of illustration, one embodiment of the invention. In the drawing:—

Fig. 1 is a top plan view of a device according to the invention.

Fig. 2 is a section on line 2—2 of Fig. 1, viewed in the direction of the arrows.

Fig. 3 is a section on line 3—3 of Fig. 2, viewed in the direction of the arrows.

Fig. 4 is a detail elevation, with parts shown in section, of a detent used in the device.

Referring to the drawing, there is shown a skate S carried by skate placing mechanism having a main support 1 bolted by hook bolts 2, directly to a track rail 3, supported on ties 4. The main support 1 has two upstanding lugs 5 which are cross drilled to provide journals for a shaft 6. On the shaft 6 is pivoted a skate placing arm 7 having hollow cylinders 8 at its ends. In the cylinders 8 are plungers 9 urged outwardly of the cylinders by springs (not shown) within the cylinders, these plungers being for a purpose to be explained below.

The skate placing arm 7 is pivotally supported on the shaft 6, and is adjustably secured thereto by an operating arm 29 pinned to the shaft 6 by pins 30, the other end of arm 29 being adjustably connected to the skate placing member 7, by screws 10 and 11, the screws 10 being threaded into the arm 29, while the screw 11 has its end bearing against such arms 29 to lock the parts in adjusted position. With this construction it will be noted that the skate placing arm 7 is adjustably connected to the shaft 6 so as to rotate with this shaft.

The shaft 6, as shown in Fig. 1, has a universal joint 12 and a driving telescopic joint 13, to permit proper alignment of the parts, the joint 13 preventing danger to the drive mechanism, (not shown) connected to the left end of the shaft 6, as viewed in Fig. 1, should the skate S, for any reason whatsoever, fail to separate from the arm 7, during operation with a car wheel.

The skate S, is of the general shape shown in the drawings, and has its forward end bifurcated to support a roller 14 to prevent sticking of the skate on the rail should it momentarily be tilted forward on its front end by a car wheel.

At the lower side of the skate are two spaced downwardly projecting posts, 15, 16, having tapered undercut grooves into which a correspondingly shaped, tapered tongue 17, carried by the plungers 9 of the skate placing arm 7, accurately fits. Due to the undercut of the groove and tongue the skate cannot be lifted off of the arm 7, and due to the taper of the groove and tongue, the skate is readily

slidable off of the arm 7, in one direction, while held from such sliding detachment in the other direction.

In order to prevent too ready sliding of the 5 skate S off of its supporting arm 7, a detent is provided. This detent comprises a cylindrical casing 18 having a seat 19 at one end for a ball 20 housed within the casing and projecting slightly therefrom. The ball 20 10 is forced outwardly of its casing by a helical spring 21, carried within the casing and bearing with one end against the ball and at the other against a spring tension adjusting plug 22 threaded into the other end of the casing. 15 The outer surface of the casing 18 is threaded at 23 and has a faced head 24 for screwing the entire detent assembly into a bore in the part 16 (Fig. 3). The inner face of the tongue 17, has a socket 25 forced therein to 20 accommodate the projecting part of ball 20. With this arrangement, it is necessary, in sliding the skate S free from the arm 7, to force the ball up out of the socket 25 and into its casing 18 against the tension of spring 25 21.

In the inactive position of the skate S, as shown in Fig. 2, the skate is adapted to be 30 adjustably supported by screws 26, passing through a plate 27 fastened to two adjacent ties at 28.

It is obvious from the above, that the 35 detent device described, furnishes a simple yet very reliable means for preventing accidental detachment of a skate from its supporting arm..

In operation, when it is desired to place the 40 skate S in operative position on the track rail, the motor means for rotating shaft 6 is set in motion, to thus rotate the arm 7 about the lugs 5 and with it the skate, until the latter rests on the rail 3. In this position a car wheel can ride up on the skate and slide the 45 skate off of its retaining tongue 17, the detent ball 20 being forced inwardly against its spring 21 during the operation.

The above specific description of a device 50 embodying this invention is given solely by way of illustration, and is not intended, in any manner whatsoever, in a limiting sense. Obviously, this invention can assume many 55 different physical forms, and is susceptible of various modifications, and all such forms and modifications are desired to be included by this invention, as come within the scope of the appended claims.

Having described my invention, I now claim:—

1. In an emergency train stop device, a 60 support, means to fix the support relative to a track rail, a skate placing mechanism carried by the support, a skate connected to the said mechanism by a slidably detachable coupling, and ball and socket detent means resisting separation of the separable parts of 65 the coupling.

2. In an emergency train stop device, a support, means to fix the support relative to a track rail, a skate placing mechanism carried by the support, a skate connected to the said mechanism by a slidably detachable coupling consisting of integral unitary socket member and a plug member, and a spring 70 pressed detent yieldingly resisting separation of the separable members of the coupling.

3. In an emergency train stop device, a support, means to fix the support relative to a track rail, a skate placing mechanism carried by the support, a skate connected to the said mechanism by a slidably detachable coupling, and a detent carried by one of the separable parts of the coupling and having a spring pressed member bearing against another of the separable parts of the coupling.

4. In an emergency train stop device, a 85 fixed support, a skate, a skate carrying arm, a slidably detachable coupling consisting of a receiving and a received member connecting the skate to the arm, and a detent within the wall of the receiving member yieldingly 90 resisting separation of the skate and arm.

5. In an emergency train stop device, a 95 fixed support, a skate, a skate carrying arm, a slidably detachable coupling connecting the skate to the arm, and a detent yieldingly resisting separation of the skate and arm, the detent including a casing carried by one member of the coupling, and a spring pressed plunger in the casing coacting with a receiving socket in another member of the coupling. 100

6. In an emergency train stop device, a 105 fixed support, a skate, a skate carrying arm, a slidably detachable coupling connecting the skate to the arm, and a detent yieldingly resisting separation of the skate and arm, the detent including a casing carried by one member of the coupling, and a spring pressed plunger in the casing coacting with a receiving socket in another member of the coupling, 110 and means for adjusting the tension of the plunger spring.

7. A slidably detachable coupling for 115 brake skates, comprising, a member having an undercut tapered groove, a beveled tapered tongue slidably receivable in the groove, and detent means resisting separation of the tongue and the groove.

8. A slidably detachable coupling for 120 brake skates, comprising, a member having a groove, a tongue slidably receivable in the groove, and a ball and socket detent means resisting separation of the tongue and the groove.

9. A slidably detachable coupling for 125 brake skates, comprising, a member having an undercut tapered groove, a beveled tapered tongue slidably receivable in the groove, a casing carried by the groove member, a spring pressed plunger projecting from the casing, 130

and a socket in the tongue normally receiving the plunger.

10. In an emergency train stop device, a support, means to fix the support relative to 5 a track rail, skate placing mechanism carried by the support, a skate connected to the said mechanism by a slidably detachable cou-

pling comprising separable plug and socket members, and a yieldable detent in the wall of said socket member resisting separation 10 of the separable members of the coupling.

In testimony whereof I affix my signature.

HERBERT B. TAYLOR.
